ABSTRACT

A concrete precasting machine in which inner and outer molds forms are supported on a vibration table. The concrete is fed to the molds through a conical shut off valve which retains excess concrete on the conveyor belt when conveyor is retracted and thus prevents overfilling of the mold and spillage of concrete on the floor. The outer mold form and cast article are supported on a pallet and are together separable from an inner mold. The machine permits practically continuous casting with a minimum of slack time between pouring operations.

CONCRETE PRECASTING MACHINE

BACKGROUND OF THE INVENTION

Field of the Invention

The present invention relates to concrete precasting machines of the vibrating table type in which the mold forms are vibrated during the concrete pouring operation.

SUMMARY OF THE INVENTION

In the present invention inner and outer mold forms are supported on a vibration table and concrete is fed between the forms with a conical valve cut off arranged to prevent spillage and overfilling of the molds.

The primary object of the invention is to provide a versatile concrete precasting machine which permits nearly continuous operation in the production of regular and odd shaped prefabricated concrete articles such as manholes, conduits and the like.

Another object of the invention is to provide a device as the type described above in which the article is removed from the molds prior to curing and supported on a pallet during curing.

A further object of the invention is to provide a highly versatile concrete precasting machine which can accomodate molds of vastly differing shapes and sizes on a flat vibration table and which can be fed concrete via a contractable conveyor and cone chute combination moveable to any desired discharge position overlying the vibration table.

Other objects and advantages will become apparent in the following specification when considered in light of the attached drawings.

BRIEF DESCRIPTION OF THE DRAWINGS

FIG. 1 is a side elevation of the invention;

FIG. 2 is a front elevation of the invention;

FIG. 3 is a horizontal sectional view taken on the line 3-3 of FIG. 2 looking in the direction of the arrows;

FIG. 3a is an enlarged vertical sectional view taken on the line 3a-3a of FIG. 3 looking in the direction of the arrows;

FIG. 4 is a top plan view of the casting mold as seen from the line 4-4 of FIG. 1 looking in the direction of the arrows;

FIG. 5 is a front elevation of the casting mold of FIG. 4;

FIG. 6 is a fragmentary vertical sectional view taken on the line 6-6 of FIG. 4 looking in the direction of the arrows;

FIG. 7 is an enlarged fragmentary vertical sectional view taken on the line 7-7 of FIG. 6 looking in the direction of the arrows;

FIG. 8 is an enlarged fragmentary horizontal sectional view taken on the line 8-8 of FIG. 1 looking in the direction of the arrows;

FIG. 9 is a fragmentary vertical sectional view taken on the line 9-9 of FIG. 8 looking in the direction of the arrows;

FIG. 10 is a top plan view of one of the cranes forming part of the invention;

FIG. 11 is a front elevation of the crane of FIG. 10 shown partially broken away and in section for convenience of illustration;

FIG. 12 is a horizontal sectional view taken on the line 12-12 of FIG. 11 looking in the direction of the arrows;

FIG. 13 is a fragmentary front elevation of a mold lock;

FIG. 14 is a horizontal sectional view taken on the line 14-14 of FIG. 13 looking in the direction of the arrows;

FIG. 15 is a fragmentary top plan view of the mold guide;

FIG. 16 is a vertical sectional view taken on the line 16-16 of FIG. 15 looking in the direction of the arrows;

FIG. 17 is a vertical sectional view taken on the line 17-17 of FIG. 16 looking in the direction of the arrows;

FIG. 18 is a fragmentary top plan view of a mold on the vibrating table;

FIG. 19 is a vertical sectional view taken on the line 19-19 of FIG. 18 looking in the direction of the arrows;

FIG. 20 is an enlarged fragmentary vertical sectional view taken on the line 20-20 of FIG. 19 looking in the direction of the arrows;

FIG. 21 is a transverse sectional view taken on the line 21-21 of FIG. 20 looking in the direction of the arrows;

FIG. 22 is a bottom plan view of the structure illustrated in FIG. 20;

FIG. 23 is a horizontal sectional view taken on the line 23-23 of FIG. 19 looking in the direction of the arrows;

FIG. 24 is a fragmentary vertical sectional view taken along the line 24-24 of FIG. 23 looking in the direction of the arrows;

FIG. 25 is a transverse sectional view taken along the line 25-25 of FIG. 24 looking in the direction of the arrows;

FIG. 26 is a perspective view of the handling crane;

FIG. 27 is a top plan view of one of the molds used with the invention;

FIG. 28 is a fragmentary vertical sectional view taken along the line 28-28 of FIG. 27 looking in the direction of the arrows;

FIG. 29 is a vertical sectional view of a manhole mold shown in position on the vibrating table;

FIG. 30 is a horizontal sectional view taken on the line 30-30 of FIG. 29 looking in the direction of the arrows;

FIG. 31 is a bottom plan view of the manhole mold as seen from the line 31-31 of FIG. 29 looking in the direction of the arrows;

FIG. 32 is an enlarged fragmentary vertical sectional view taken on the line 32-32 of FIG. 29 looking in the direction of the arrows;

FIG. 33 is an exploded elevation of another mold used in the apparatus of the present invention, shown partially broken away and in section for convenience of illustration;

FIG. 34 is an enlarged fragmentary horizontal sectional view taken on the line 34-34 of FIG. 33 looking in the direction of the arrows;

FIG. 35 is an enlarged fragmentary horizontal sectional view taken on the line 35-35 of FIG. 33 looking in the direction of the arrows;

FIG. 36 is a fragmentary sectional view taken on the line 36—36 of FIG. 35 looking in the direction of the arrows;

FIG. 37 is a perspective view of a rung adapted to be inserted into the wall of a manhole cast by the apparatus of the present invention;

FIG. 38 is a fragmentary horizontal sectional view of a portion of the manhole produced in the apparatus of FIG. 33 showing a rung in solid lines prior to insertion in the wall of the manhole, the dotted lines showing the rung in place in cavities in the manhole wall;

FIG. 39 is a side elevation view of the mechanism illustrated in FIG. 35 and 36 with parts broken away for convenience of illustration; and

FIG. 40 is a perspective view of a manhole produced by the apparatus of the present invention, shown partially broken away and in section for convenience of illustration.

DESCRIPTION OF THE PREFERRED EMBODIMENTS

Referring now to the drawings in detail wherein like reference characters indicate like parts throughout the several figures the reference numeral 50 indicates generally the apparatus of the present invention.

The apparatus 50 includes a vibrating mold support indicated generally at 51 consisting of a vibration table 52 mounted on springs 53 extending upwardly from a base 54. The vibration table 52 and base 54 are disposed in a floor recess 55 with the upper surface of the vibration table 52 generally aligned with the surface of the floor.

The apparatus 50 includes a tower 56 of generally rectangular form and having an upright angle iron member 57 in each inside corner thereof. A vertical rail 58 is secured to each of the angle iron members 57 by bolts 59. The angle iron frame member 57 is secured to the tower 56 by bolts 60 which extend through transverse slots 61 in the tower 56. The angle iron member 57 is a horizontally adjustable on the tower 56 and an adjustment screw 62 engages against the angle iron member 57 to support it in adjusted position.

A concrete conveyor generally indicated at 63 includes a pair of channel tracks 64 which extend upwardly and inwardly from a base frame 65 to a power frame 66 mounted on top of the tower 56.

A traveling bin 67 is mounted on rollers 68 which engage in the channel tracks 64. A cable 69 is secured to the bin 67 and is wound on a winch 70 mounted on the power frame 66. An electric motor 71 drives the winch 70 through a power transmission 72. The electric motor 71 and power transmission 72 are both mounted on the power frame 66.

A conveyor 73 conveys concrete from the mixer 74 to the bin 67 when the bin 67 is in its lowermost position. As the bin 67 is raised on the channel tracks 64 by the winch 70 the upper roller 68 thereof moves outwardly in a horizontal track 75 and the lower roller 68 continues on up in the channel track 64. This movement of the rollers 68 causes the bin 67 to upend, as shown in dotted lines in FIG. 2, dumping its contents into the top of the tower 56.

A generally rectangular carriage 76 is mounted for vertical reciprocation in the tower 56 and has a plurality of flanged wheels 77 journaled on stub shafts 78 fixed to the carriage 76. The flanged wheels 77 engage the track 58 to guide the carriage 76 for vertical move-

ment within the tower 56. A plural section hydraulic ram 79 is mounted centrally of the tower 56 and is secured to the lower end of the carriage 76 for moving the carriage 76 vertically in the tower 56.

5 A hopper 80 is secured in the top of the carriage 76 in a position to receive concrete dumped therein from the traveling bin 67.

10 A generally horizontal frame 81 is mounted for horizontal reciprocation on rollers 82 within the carriage 76. A hydraulic cylinder 83 is mounted in the carriage 76 and has a piston rod 84 connected to the frame 81 to reciprocate the frame 81 horizontally in the carriage 76. An endless belt conveyor 85 is mounted on the frame 81 on a plurality of rollers 86 with the belt 85 extending for the full length of the frame 81. The belt 85 is trained over a large motor driven drive roller 87 at one end and over an idler roller 88 at its opposite end. The hopper 80 receiving concrete from the bin 67 directs all of it onto the conveyor belt 85 for movement 15 thereon.

20 A concrete delivery unit indicated generally at 89 is mounted on the outer end of the horizontal frame 81 and travels therewith as the horizontal frame 81 is horizontally reciprocated by the hydraulic cylinder 83 and piston rod 84. The concrete delivery unit 89 includes an upright generally rectangular frame 90 secured to the outer ends of the horizontal frame 81 and extending upwardly therefrom. A horizontal frame 91 is rigidly secured to the upright frame 90 and extends forwardly 25 therefrom. Adjustable angular braces 92 extend from the upper portion of the upright frame 90 to the outer end portion of the horizontal frame 91 to assist in supporting and levelling the horizontal frame 91.

30 The frame 91 is generally circular and has a circular depending channel flange 93 secured thereto and carrying a plurality of flanged rollers 94 on the inner vertical face thereof. A deflector plate 95 is secured to the frame 91 and is spaced outwardly from the conveyor belt 85 to direct concrete delivered by the belt 85 35 downwardly through the horizontal frame 91.

35 A circular funnel member 96 is positioned within the channel flange 93 and has a circular angle track 97 secured to the outer face thereof and supported on the flanged rollers 94 as can be plainly seen in FIG. 3a. The funnel member 96 has an upper cylindrical portion 98 and a lower inwardly converging portion 99 integrally secured thereto and depending therefrom.

40 The funnel member 96 is illustrated with its axis coaxial with the axis of the circular frame 91 but it should be understood that the funnel member 96 may be positioned off center to assist in the casting of eccentric cones, as well as, square and rectangular items.

45 A chute 100 is secured on aligned pivot pins 101 to opposite sides of the lower end of the funnel member 96. The chute 100 underlies the funnel member 96 and is adapted to receive concrete material therefrom.

50 A hydraulic cylinder 102 is mounted on the frame 91 centrally thereof in a perpendicular position. A piston rod 103 extends through the hydraulic cylinder 102 and projects substantially therebelow. A conical valve 104 is secured at its upper end to a fitting 105 detachably secured to the piston rod 103 and at its lower end to a fitting 106 also detachably secured to the piston rod 103 at a point spaced well below the fitting 105. The conical valve 104 diverges downwardly and has its larger diameter slightly greater than the smallest diameter of the downwardly converging portion 99 of the 55 60 65

funnel member 96. The conical valve 104 is adapted to be raised and lowered by the hydraulic cylinder 102 so as to engage the funnel member 96 at its lower end to prevent the flow of concrete therefrom. The conical valve 104 is spaced from the funnel member 96 at its upper limit of travel to permit the flow of concrete from the funnel member 96.

A rotary hydraulic motor 107 is mounted in a bracket 108 carried by the frame 91 and has a belt 109 extending therefrom around the cylindrical portion 98 of the funnel member 96 engaging between a pair of annular ribs 110. Rotation of the hydraulic motor 107 rotates the funnel member 96 along with the chute 100 to deliver concrete to the desired discharge point.

The horizontal frame 81 is aligned with the center of the vibration table 52 so that the concrete delivery unit 89 can be moved outwardly to overlie the center of any mold mounted on the vibration table 52.

The vibrating mold support 51 includes the horizontal flat vibration table 52 which carries a plurality of rotary air or electric vibrators 111 secured to the underside thereof and each having its horizontal axis of rotation arranged perpendicular to the adjacent vibrator 111.

A plurality of generally rectangular guide blocks 112 having a sloping end wall 113 are detachably secured to the vibration table 52 to guide a mold base 114 into center position on the vibration table 52. The blocks 112 each have a guide pin 115 which are adapted to engage in guide bores 116 in the vibration table 52.

The guide block 112 is positioned over an elongate slot 117 in the vibration table 52 and a pair of V blocks 118 are arranged on opposite sides of the slot 117 beneath the table 52 in spaced parallel relation. A T bolt 119 extends through a vertical bore 120 in the guide block 112 and has a T head 121 on its lower end which is adapted to be moved downwardly through the slot 117 and turned at right angles to engage in the V blocks 118 as can be seen in FIGS. 15, 16 and 17. A nut 122 is threaded onto the upper end of the T bolt 119 to lock the guide block 112 in its adjusted position on the vibration table 52.

A T bolt 123 extends vertically through the mold base 114 and through an elongate slot 124 in the vibration table 52. A plurality of depending lugs 125 are secured to the underside of the vibration table 52 in spaced apart relation on opposite sides of the slot 124 to receive a T head 126 on the T bolt 123. The T bolt 123 is moved downwardly through the elongate slot 124 and the T head 126 is turned perpendicularly to the slot 124 to engage the lugs 125. A nut 127 is threaded onto the T bolt 123 to lock the mold base 114 to the vibrating table 52.

Referring now to FIGS. 3 and 10 through 12 a pair of identical hoists 128 and 129 are positioned on opposite sides of the vibration table 52 for reasons to be assigned.

The hoists 128 and 129 each include an upright hollow cylindrical post 130 extending upwardly from a base plate 131. A plurality of angular gusset plates 132 are secured to the base plate 131 and to the post 130 to strengthen the post 130.

An I-beam 133 extends horizontally above the post 130 and is pivotally secured to the post 130 by a pivot bolt 134 which extends vertically through the top 135 of the post 130 and through the center of the bottom flange 136 of the beam 133. The web 137 of the I-beam

133 is cut away at 138 to permit the pivot bolt 134 to extend through the center of the web 136 intermediate the opposite sides thereof. A generally rectangular skirt 139 depends from the I-beam 133 and is rigidly secured thereto. The skirt 139 encompasses the upper portion of the post 130 and has a plurality of roller members 140 journaled between vertically spaced flanges 141 rigidly secured to the inner corners of the skirt 139. The rollers 140 bear against the outer face of the post 130 to support the skirt 139 from the post 130 to provide additional bracing support for the beam 133.

A table 142 is rigidly secured to the post 130 and extends horizontally outwardly therefrom and has a pivot 143 secured to its outer end. A hydraulic cylinder 144 is pivotally mounted on the pivot 143 at one end and has a piston rod 145 secured to a boss 146 by means of a pivot pin 147. The boss 146 is rigidly connected to the lower end portion of the skirt 139. Operation of the hydraulic cylinder 144 turns the skirt 139 and beam 133 with respect to the post 130 about the pivot bolt 134. A hydraulic lock pin assembly 148 is secured to the skirt 139 and has a lock pin 149 which is vertically moved to engage in a keeper socket 150 in the table 142 locking the beam 133 in adjusted position about the post 130. A plurality of keeper sockets 150 may be provided in the table 142 so as to lock the beam 133 in a plurality of adjusted positions.

A hydraulic cylinder 151 is secured by a pivot pin 152 to the outer end of the beam 133 and extends generally perpendicularly downwardly therefrom. A piston rod 153 reciprocates in the hydraulic cylinder 151 and has a mold pressure head 154 detachably secured to the lower end thereof.

The hoist 129 is moved by hand and does not include the pivoting structure using the hydraulic cylinder 144, as described above for hoist 128.

In FIG. 26 a fragmentary portion of the beam 133 forming part of the hoist 129 is illustrated. An electric chain winch 155 is secured to the outer end portion of the beam 133 and has a depending hoist block 156 carried by a chain 157. The hoist block 156 is provided with a hook 158 to which is secured a beam 159 having securing chains 160 depending from opposite ends thereof.

Referring now to FIGS. 4 through 7, 13 and 14 one of the molds used with the invention is illustrated generally at 161. The mold 161 is supported on the mold base 114 having a plurality of channel frame members 162 secured to the underside thereof. The mold base 114 has a relatively large central opening 163 formed therein for reasons to be assigned.

A generally cylindrical inner mold form 164 is supported on the base 114 surrounding the opening 163. An upper channel frame member 165 is secured to the upper inner edge of the inner mold form 164 and a lower channel frame member 166 is secured to the lower inner face of the inner mold form 164 to assist in retaining the shape of the inner mold form 164.

A generally flat circular table 167 is supported on the upper end of the inner mold form 164 and has a pair of rigid legs 168 depending from a point closely adjacent the center thereof for reasons to be assigned. A plurality of socket members 169 are secured to the under side of the table 167 in depending relation adjacent the peripheral edges thereof. A leg 170 is detachably mounted in each of the sockets 169 and releasably secured therein by a transverse pin 171. A pair of air

jets 172 extend through the table 167 on opposite sides thereof and are connected to an air pressure pipe 173 for reasons to be assigned.

An elongate slot 174 opens through the center of the table 167 and a pair of V blocks 175 are secured to the under side of the table 167 on opposite sides of the slot 174 and parallel thereto. A bolt 176 having a T head 177 is engaged through the slot 174 and turned to engage in the V block 175. A nut 178 on the threaded upper end of the bolt 176 secures a cylindrical core 179 to the table 167. A loop 180 is welded to the underside of the table 167 adjacent the center thereof for reasons to be assigned.

An outer mold form generally indicated at 181 includes a pair of semi-cylindrical halves 182, 183. The halves 182, 183 meet along a pair of vertical joints 184. Upper channel frame members 185 are secured to each of the halves 182, 183 adjacent the upper end thereof and lower channel frame members 186 are secured thereto adjacent the lower edges thereof. Upright channel frame members 187 extend between the channel frame members 185, 186 intermediate their opposite ends. A hook element 188 is secured to each of the halves 182, 183 at opposite sides thereof for reasons to be assigned. A latch pin 189 is rigidly mounted on each of the upright channel frame members 187 to be engaged by an over dead center tightening lever 190 mounted on the mold base 114 to lock the outer mold form 181 to the base 114. Latch pins 191 are secured to each of the halves 182, 183 in vertically spaced relation adjacent the vertical joint 184. An over dead center tightening lever 192 is secured to the opposite half 182, 183 to cooperate with a respected latch pin 191 to hold the halves 182, 183 together. A plurality of loops 193 are secured to the mold form 181 adjacent the upper edge thereof to provide means for disassembling the semi-cylindrical halves 182, 183 as will be described.

A generally Z shaped spigot pallet 194 of generally cylindrical form is engaged between the inner mold form 164 and the outer mold form 181 at the bottom thereof supported on the mold base 114.

In using the mold 161 the mold base 114 is mounted on the vibration table 52 as illustrated in FIGS. 15 through 17 following which the inner mold form 165 is positioned on the mold base 114. The spigot pallet 194 is engaged about the inner mold form 164 and the table 167 with legs 168 and 170 attached is inserted in the inner mold form 164 and supported on the upper face thereof. The air pressure pipe 173 is then connected to a source of air under pressure. The outer mold form 181 is assembled and inserted over the inner mold form 164 and locked down to the mold base 114 by the tightening lever 190 and latch pins 189.

The air or electric rotary vibrators 111 are then energized to vibrate the table 52 and the mold 161 thereon.

Concrete from the concrete mixer 74 is then fed on the conveyor 73 to the bin 67 and from there into the hopper 80 where it is fed onto the conveyor belt 85 and into the funnel member 96. The conical valve 104 is raised by the hydraulic cylinder 102 and the concrete flows through the chute 100 into the mold 161. The chute 100 is rotated about the axis of the shaft 103 by operation of the rotary hydraulic motor 107 so that the concrete feeding into the mold 161 is distributed evenly thereabout. The concrete builds up in the mold

161 until the table 167 is covered with concrete to a thickness substantially equal to the thickness of the walls formed between the inner mold form 164 and the outer mold form 181.

5 The concrete has sufficient water to complete the chemical reaction involved in the hardening of the concrete but insufficient to produce a wet or fluid material. Upon the completion of the filling of the mold 161 the vibration has caused the mold 161 to fill completely and to compact therein so that the concrete obtains initial set almost immediately. The outer mold form 181 along with the pallet 194 and table 167 with the molded article therein are then moved as a unit to a curing location leaving the inner mold form 164 on the mold base 114. The outer mold form is then stripped away so that the table 167 and pallet 194 support the center portion and lower edge portion of the concrete article during the curing thereof. The concrete article cast in the mold 161 is the bottom section of a manhole which is cast in inverted position.

15 While not illustrated in FIGS. 4 through 6 a pressure head such as that illustrated in FIGS. 27 and 28 is normally secured to the mold 161 by means of slotted brackets 195 mounted on the outer mold form 181 in circumferentially spaced relation. The function of the pressure head when used is to compact the concrete in the mold 161.

20 The air jets 172 provide means for separating the table 167 from the cured concrete article to permit the table 167 to be removed therefrom. The loop 180 permits the attachment of hydraulic rams to remove the table 167 in an emergency.

25 In FIGS. 18 and 19 another mold is indicated generally at 196. The mold 196 includes a mold base 114 secured to a vibrating table 52 as described above. An inner mold form 197 of generally cylindrical form is supported by an upper channel frame member 198 which is secured to the upper inner face thereof and extends above the upper edge of the inner mold form 197. A lower channel frame member 199 is secured to the lower inner face of the inner mold form 197 at the lower edge thereof. A central channel frame member 200 is secured to the inner mold form 197 intermediate the upper channel frame member 198 and the lower channel frame member 199. The channel frame members 198, 199 and 200 each extend generally horizontally and are parallel to each other. A plurality of transversely extending frame members 201 extend across the upper portion of the inner mold form 197 and are secured thereto. The frame members 201 are arranged in perpendicularly extending spaced parallel pairs to form a central pocket 202. An air or electric rotary vibrator 203 is mounted in the pocket 202 with its axis of rotation extending vertically perpendicular to the axis of rotation of the rotary air or electric vibrators 111. The pressure head 154 covers an inner dome 204 supported on and welded to the upper edge of the inner mold form 197 in engagement with the outer face of the upper channel frame member 198. A generally cylindrical Z shaped bell pallet 205 is supported on the mold base 114 completely surrounding the lower end portion of the inner mold form 197. An outer mold form indicated generally at 206 is constructed substantially the same as the outer mold form 181.

30 35 40 45 50 55 60 65 66 A latch 207 is secured to the outer mold form 206 and has an elongate latch pin 208 which is provided with a semi-cylindrical extension 209. A coil spring 210

in the latch 207 normally urges the latch pin 208 through a semi-cylindrical aperture 211 in the outer mold form 206. The semi-cylindrical extension 209 engages under the bell pallet 205 to lock the outer mold form 206 thereto. When it is desired to disengage the latch pin 208 from the bell pallet 205 the latch pin 208 is drawn outwardly of the latch 207 against the tension of the spring 210 so that the extension 209 is completely out of the aperture 211, the latch pin 208 is then turned on its axis so that the extension 209 will not align with the aperture 211 and the latch pin 208 is then released and merely engages against the outer face of the outer mold form 206.

Concrete is filled into the space between the inner mold form 197 and the outer mold form 206 in the same manner that concrete was fed to the mold 161. The compression head 154 of FIGS. 27 and 28 is then attached to the outer mold form 206 to apply the compacting pressure to the concrete in the mold 196. A generally Z-shaped cylindrical spigot pallet 212 is carried by the head 154 on latches 293 such as are illustrated in FIGS. 33 and 34 and is positioned between the mold forms 197, 206 at the upper ends thereof.

The mold pressure head 154 illustrated in FIGS. 10, 11, 27 and 28 will now be described in detail. The mold pressure head 154 includes a dome 213 spaced above the dome 204 and a bearing plate 294 is integrally secured to the lower end portion of the dome 213 and extends toward the dome 204. The plate 214 engages against a plurality of pads P which extend upwardly from the upper portion of the spigot pallet 212. The outer mold form 206 is provided with a plurality of slotted brackets 195 spaced thereabout. The pressure head 154 is provided with a plurality of pairs of spaced apart parallel ears 216 having a hydraulic cylinder 217 pivotally mounted therebetween on pivot pins 218. Each of the hydraulic cylinders 217 have a piston rod 219 depending therefrom and carrying a T head 220 on its outer end. A small hydraulic cylinder 221 has one end secured between a pair of ears 222 mounted on the pressure head 154 with a pivot pin 223. The piston rod 224 of the hydraulic cylinder 221 extends between a pair of ears 225 on the upper end of the hydraulic cylinder 217 and is connected thereto by a pivot pin 226.

With the pressure head 154 in place on the mold 206 the small hydraulic cylinders 221 are actuated to swing the hydraulic cylinders 217 into vertical position with the piston rod 219 thereof engaged in the slot of the slotted bracket 195 and the head 220 lying beneath the bracket 195. The hydraulic cylinder 217 is then actuated to draw the piston rod 219 upwardly engaging the head 220 with the bracket 195 and drawing the pressure head 154 downwardly. Pneumatic pressure is then introduced under the dome 213 to apply pressure to the spigot pallet 212 released from the latch 293, so as to compress the concrete in the mold 196 by forcing the spigot pallet 212 downwardly therein.

The vibrator 203 produces a cyclic motion to assist in the compaction time of the concrete at the spigot and also helps to vibrate the relatively dry mix in much less time at the walls.

The tightening levers 192 are longitudinally adjustable and may be used to apply pressure in a direction to separate the mold halves 182, 183 as well as in the opposite direction to draw the mold halves 182, 183 together.

In FIGS. 29 through 32 and 40 a modified form of the invention is illustrated wherein a relatively rectangular concrete product is formed. A generally rectangular mold indicated generally at 228 is illustrated in detail in FIGS. 29 through 32. While in this mold a concrete manhole having a generally rectangular horizontal cross-section is cast in inverted position, it is to be understood that other forms of concrete articles may be produced using the inventive concepts of the apparatus.

The mold 228 includes an outer mold form 229 supported on a mold base 114' and an inner mold form 230 also supported on the mold base 114' in inwardly spaced relation to the outer mold form 229. The mold base 114' is secured to the vibration table 52 in the same manner that the mold base 114 is secured to the vibration table 52 described above. A T shaped generally rectangular pallet 231 is positioned between the inner mold form 230 and the outer mold form 229 and is also supported on the mold base 114'. The inner mold form 230 is collapsible to permit it to be removed after the concrete article has been cast. The inner mold 230 includes a pair of two piece side walls 232 which are pivotally secured together at 233 and a pair of two piece end walls 234 pivotally secured together at 235. The end walls and side walls are pivotally secured together at 236. The side walls 232 are adapted to move inwardly pivoting about their pivots 233 and pivots 236 and the end walls 234 are adapted to move inwardly pivoting about their pivots 235 and 236.

A shaft 237 extends vertically through the center of the inner form 230 and has a handle 238 secured to its lower end. A pair of cam plates 239 are secured in vertically spaced relation to the shaft 237 with each cam plate 239 having a plurality of cam slots 240 formed therein. A generally rectangular post 241 is secured to and extends upwardly from the mold base 114' intermediate each of the end walls 234 and the shaft 237. A generally rectangular post 242 is secured to and extends upwardly from the mold base 114' intermediate the side walls 232 and the shaft 237. A cylindrical guide 243 extends through each of the post 241 adjacent the upper and lower ends thereof and a link 244 is slidably mounted in each of the guides 243. The link 244 is connected to the center of the end walls 234 at one end and to an adjacent slot 240 in the cam plate 239 at the other end. A cylindrical guide 245 extends through the post 242 adjacent the upper and lower ends thereof and each of the guides 245 have a link 246 slidably mounted therein and connected at its inner end to a slot 240 in the cam plate 239 and its outer end to the center of the side walls 232. Rotation of the shaft 237 by means of the handle 238 rotates the cam plates 239 and draws the links 244, 246 inwardly collapsing the end walls 234 and the side walls 232 to disengage them from the concrete article cast in the form 228.

An upright pipe 247 is secured to each of the post 241 to serve as vertical guides as described below. A generally rectangular table 248 is supported on the upper ends of the inner mold form 230 and has a plurality of tubular legs 249 rigidly secured thereto and depending therefrom. The legs 249 engage in the guide pipes 247 for reasons to be assigned. An upwardly extending tapered core plug 250 is rigidly secured to the upper end of the table 248 and extends above the outer mold form 229. The core plug 250 has an axial bore 251 extending therethrough for reasons to be assigned.

A bar 252 is adapted to extend across the mold 228 engaging the upper end of the outer mold form 230 with the core plug 250 extending upwardly through a slot 253 in the lower face of the bar 252. A mushroom head 254 is formed on the upper end of the core plug 250. An air fitting 255 is secured to the upper end of the core plug 250 communicating with the bore 251. A slotted plate 256 has a keyhold slot 257 therein so that the bar 252 may be attached to the core plug 250 by dropping the keyhole slot over the mushroom head 254 and moving the slotted plate 256 so as to engage it under the mushroom head 254 in the position illustrated in FIG. 29. A screw pressure member 258 extends through the bar 252 and engages against a flange 259, on the outer mold form 229 to rock the bar 252 upwardly thus locking it to the core plug 250. The bar 252 is similarly connected to the upper T-head of the bolt 176, illustrated in FIGS. 5 through 7, for the same purpose.

In the use of the mold 228 the mold is assembled as illustrated in FIGS. 29 and 30 with the bar 252 left off for the time being. The mold 228 is filled with concrete from the vibrators 111 as described in the other forms of the invention above. A pressure head (not shown) with flat plate attached is used to apply pressure to the concrete at the top portion of the base being formed. The outer mold form 229 has a plurality of latches 207 which engage under the edge of the pallet 231 in the same manner as the latches 207 engage the pallet 205 above. After the completion of the pouring of the concrete, and the application of top pressure, the bar 252 is attached to the core plug 250 and to the outer mold form 229 as described above. The connections between the inner and outer mold forms 230, 229 to the mold base 114 are disconnected and the inner mold form 230 is collapsed. The outer mold form 229 is then connected to a traveling hoist (not shown) and the outer mold form 229, table 248 and pallet 231 along with the concrete article are raised off the mold base 114 leaving the inner mold form 230 thereon. The remainder of the mold 228 is then transported to a curing location where it is deposited with the legs 249 of the table 248 in engagement with the floor. The pallet 231 also engages the floor at this time. The latches 207 are then released and the bar 252 is disconnected from the core plug 250 to permit the outer mold form 229 to be stripped from the case concrete article. The cast concrete article is then supported on the table 248 and the pallet 231 where it remains until curing is complete. The outer and inner mold portions of the mold 228 may then be reused with additional pallets 231 and tables 248. After the manhole has cured the table 248 and core plug 250 are removed and the hole left by the core plug 250 is filled with concrete prior to installing of the manhole in position.

In FIG. 40 a manhole indicated generally at 260 is illustrated in the inverted position in which it was cast in the mold 228.

Referring now to FIGS. 33 through 39 another modified form of the invention is illustrating wherein a mold indicated generally at 261 is provided for forming a cylindrical manhole 262 open at the top and bottom and having a plurality of steps 263 secured thereto to permit vertical travel of the user of the manhole. The mold 161 includes an inner mold form 264 supported on a mold base 114 which also supports an outer mold form 265 and a bell pallet 266 extending between the inner

mold form 264 and the outer mold form 265 at the lower ends thereof. A mechanism generally indicated at 267 is provided for forming sockets 268 in the manhole 262 to receive the steps 263. The mechanism 267 includes a plurality of pairs of outwardly diverging sleeves 269, 270 secured to the inner mold 264 in generally horizontal relation. The sleeves 269, 270 are connected by horizontal yokes 271 which encompass the sleeves 269, 270 intermediate their opposite ends. 5 A cylindrical plunger 272 is mounted for reciprocation in the sleeve 269 and has a rack gear 273 formed along one face thereof. The sleeve 269 is cut out at 274 to expose the rack gear 273 for meshing with a spur gear 275 journaled on a stub shaft 276 mounted in the yoke 271. A pin 277 extends up from the plunger 272 engaging in an elongate slot 278 in the sleeve 269 to prevent the plunger 272 from turning in the sleeve 269. An angle stop 279 is secured to the sleeve 269 to prevent the plunger 272 from moving out of the sleeve 269 and 10 jamming the spur gear 275. A plunger 280 is slidably mounted in the sleeve 270 and has a rack gear 281 formed on one face thereof and exposed through a cut out 282 in the sleeve 270 to mesh with a spur gear 283 fixed to a shaft 284 which extends upwardly through the mold base 114 and through all of the yokes 271 to the uppermost of the sleeves 269, 270. The shaft 284 is provided with a handle 285 on its lower end by which the shaft 284 may be rotated. The spur gears 275, 283 are meshed so that upon rotation of the shaft 284 the plunger 272 and the plunger 280 are each moved outwardly of their sleeves 269, 270 to project into the space in which the manhole 262 is to be cast. The plunger 280 is provided with a pin 286 which projects upwardly through an elongate slot 287 in the sleeve 270 to prevent the plunger 280 from turning in the sleeve 270. An angle stop 288 is secured to the inner end of the sleeve 270 to prevent the plunger 280 from moving out of the sleeve 270 to jam the spur gear 283. 15 20 25 30 35

40 The sockets 268 formed by the plungers 269 diverge outwardly so that their axes are at an angle to the axis of the legs of the step 263. The legs of the step 263 are serrated at 289 to improve the grip when cementing the steps 263 into the sockets 268.

45 In FIGS. 33, 34 a modified pressure head 290 is illustrated in which the spigot pallet 291 is detachably secured to the pressure head and moves therewith. The spigot pallet 291 has an annular flange 292 extending thereabout and a latch 293 is adapted to engage under the flange 292 to secure the pressure head 290 thereto. The latch 293 includes a vertical shaft 294 journaled in the edge of the pressure head 290 and having a rotary cam latch element 295 rigidly secured to the lower end thereof. A lever 296 is secured to the upper end of the shaft 294 as can be seen in FIG. 34.

50 A hydraulic cylinder 297 is pivotally secured at 298 to the pressure head 290 and has a piston rod 299 connected to the lever 296 by a pivot 300. Operation of the hydraulic cylinder 297 will move the piston rod 299 and rotate the shaft 294 to move the cam latch element 295 into and out of engagement with the annular flange 292. When using the flat plate under the pressure head, the same procedure is used.

55 60 65 One important advantage in the use and operation of the present invention is that both the inner and outer mold forms may be stripped from the concrete article almost as soon as the casting is complete to permit the

re-use of the inner and outer mold forms without waiting for the concrete to cure.

The hoist 128 is used exclusively for carrying the pressure head 154 to and from its operation position. The hoist 129 is used for positioning the mold parts on the vibration table during the assembly of the mold. It may also be used in removing the inner mold following the casting of the concrete article.

During the curing of the concrete the open ended manhole is supported on the lower pallet and a closed end form is supported on the lower pallet and a table supported on independent legs. The reuse of the inner and outer mold forms and mold base during the period when the concrete is curing materially reduces the investment required in these parts for a high speed casting operation for manufacturing multiple manhole elements.

In using the pressure head for compacting the concrete a force of eight thousand pounds pressure distributed over the four foot diameter of the molds is obtained producing an extremely dense concrete.

While the apparatus has been disclosed without illustrating reinforcing wires in the concrete articles it should be understood that the concrete articles may be reinforced with conventional reinforcing elements.

MODE OF OPERATION

The procedures for casting the base section of a concrete manhole without collapse of the roof of the base section in its inverted position of casting is as follows:

1. Collapsible inner mold is positioned on and locked to the mold base which has been locked to the vibration table 52.

2. The table for supporting the roof of the base section is then supported on the upper edges of the inner mold with its legs extending downwardly therein. A tapered core plug secured thereto extends upwardly therefrom.

3. The spigot pallet is set on the floor under the hoist beam.

4. The outer mold is then engaged about the pallet and locked to the pallet.

5. The hoist is then operated to lift the assembled outer mold and pallet placing it on the mold base 45 around the inner mold.

6. Inner mold is expanded to lock inside of pallet.

7. Outer mold is locked to mold base.

8. Concrete is then fed through the funnel member and distributed by the chute in between the inner and outer molds with vibration applied simultaneously. Upon completion of wall section concrete is fed onto the roof section table while continuing the simultaneous vibration. A pressure head is then secured to the mold and pressure is applied to the concrete.

9. The conical valve in the funnel member is closed as soon as the correct amount of concrete has been dispensed to prevent concrete dropping on already filled mold and on floor as the conveyor retracts.

10. Pressure head is removed and bar is installed on top of outer mold.

11. Inner mold is collapsed by turning the handle.

12. Using overhead crane or fork lift truck the bar, outer form, the concrete article, the roof section table, and the pallet are all lifted from the mold base leaving the inner form on the mold base.

13. Deposit the lifted assembly of paragraph 12 on the floor and remove the bar.

14. Pull away the outer form from the concrete article leaving the article to cure supported on the pallet and the roof section table with its legs resting on the floor to support the concrete on top of the table.

15. Following the curing of the concrete article it is raised and the table is removed therefrom using air pressure.

16. Finally the concrete article is inverted.

It should be noted that the concrete article is compacted by the vibration and immediately upon completion of the concrete pour has strength sufficient to prevent slumping when the inner and outer molds are stripped therefrom.

Having thus described the preferred embodiments of the invention it should be understood that numerous additional structural modifications and adaptations may be resorted to without departing from the spirit of the invention.

What is claimed is:

1. In a concrete casting apparatus, a funnel member, means for delivering concrete to said funnel member, a chute, having its upper end secured to said funnel member for receiving concrete delivered from said funnel member, a vibrating mold support table positioned below said funnel member, a mold base supported on said table, a split outer mold form supported on said mold base, an inner mold form supported on said mold base inwardly of and spaced from said outer mold form, a pallet extending between and contacting said inner and outer mold forms at the lower ends thereof, said chute positioned to deliver concrete from said funnel member to the space between said inner and outer mold forms, a tower, and a carriage vertically movable in said tower, said means for delivering concrete to said funnel member including a generally horizontal belt conveyor, means in said carriage supporting said conveyor for generally horizontal movement of said conveyor, said funnel member being secured beneath the outer end of said conveyor, a second table detachably supported on the upper end of said inner mold form, said chute delivering concrete to the space overlying said last-named table, and means for moving said outer mold form, said pallet, the molded concrete article and simultaneously moving said second table all from said base support to a curing position leaving said inner mold on said vibration table.

2. An apparatus as claimed in claim 1 including legs secured to and depending from said second table and extending downwardly within said inner mold form for supporting said second table in the curing position.

3. A device as claimed in claim 1 including a pressure head positioned over the upper edge of said outer mold, means detachably secured to said pressure head for engaging the upper surface of the poured concrete, and means on said pressure head for drawing said pressure head toward said outer mold to apply pressure to the upper surface of the concrete.

4. A device as claimed in claim 3 including means detachably securing the concrete upper surface engaging means to said pressure head.

5. A device as claimed in claim 4 wherein said means for engaging the upper surface of the poured concrete comprises a molding pallet.
